UNITED STATES PATENT OFFICE.

ARTHUR L. HALLIDAY, OF YONKERS, NEW YORK, ASSIGNOR TO THE
BIGELOW CARPET COMPANY, OF CLINTON, MASSACHUSETTS.

DESIGN FOR A CARPET.

SPECIFICATION forming part of Design No. 12,413, dated August 16, 1881.

Application filed July 14, 1881. Term of patent 34 years.

To all whom it may concern:

Be it known that I, ARTHUR L. HALLIDAY, of Yonkers, in the county of Westchester and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure *n* is a stripe containing a series of bars set parallel with each other and perpendicular to the length of the stripe.

The figure *B* is a stripe parallel to the stripe *n*, containing an ornamental pattern of figures resembling small shrubs or flowers set in regular order.

The figures *e*, contained principally in the stripe *B* and partly in the stripe *A*, resemble crosses with arms of equal length.

The stripe *A* contains the figure *b*, composed of a center of open roses with projecting leaves, sprays, and branches.

The branch *e*, projecting from the figure *b*, extends into the stripe *B*, and consists of a bunch of flowers set on a stem.

The figure *f* projects from one of the crosses *e*, and consists in a leafy branch with a flower resembling the spokes of a wheel at its end. From the other figure *e* projects the figure *o*,

a leafy branch interspersed with mossy sprays.

The figure *I* consists of a central leaf-like figure with projecting branches and leaves.

The figure *g* is a stripe containing a series of parallel bars running across it.

The figure *b* extends into the stripe *g* and occupies the middle thereof.
